ENGINE SPEED CONTROL BY MANIFOLD DEPRESSION

Filed May 14, 1929

UNITED STATES PATENT OFFICE

EDWIN M. POST, JR., OF NEW YORK, N. Y., ASSIGNOR TO INTERNATIONAL MOTOR COMPANY, OF NEW YORK, N. Y., A CORPORATION OF DELAWARE

ENGINE SPEED CONTROL BY MANIFOLD DEPRESSION

Application filed May 14, 1929. Serial No. 363,044.

The present invention relates to devices for controlling the output of a generator by varying a resistance in the field thereof. More specifically, the invention embodies an improved generator output controlling mechanism adapted particularly for use in connection with the gasoline electric type units, wherein an electric generator is driven by an internal combustion engine. The field resistance of the generator is controlled by the depression in the intake manifold of the engine in such manner that an increase in the engine output produces a corresponding increase in the generator output.

In the operation of power units of this character, it is desirable to vary the generator output in accordance with the capacity of the engine to assume greater loads. This invention embodies a means for controlling the generator output in the above manner through the instrumentality of the vacuum, or depression in the intake manifold of the engine. This vacuum is utilized as a controlling medium without affecting the usual manual controlling mechanism, such as a manual throttle valve which would ordinarily increase the vacuum in the manifold upon throttling the engine.

An object of this invention is to provide an improved and effective controlling mechanism of the above character, operated by the vacuum, or depression in the intake manifold of the engine.

A further object of the invention is to provide a construction of the above character which is controlled by a governor which varies the effective depression exerted upon the controlling means for the field resistance of the generator.

A further object of the invention is to combine a mechanism of the above character with the usual manual throttle control in such manner that the manual actuation of the throttle does not affect the means for varying the generator output.

Further objects of the invention, not specifically enumerated above, will be apparent as the description thereof proceeds in connection with the accompanying drawing, wherein the single figure shows the manner in

which the riser from the carburetor to the intake manifold is constructed to afford a source of depression for varying the field resistance of the generator.

Referring more specifically to the above drawing, *a* designates a carburetor of desired form having a riser formed of two sections *a'* and *a''*. An intermediate section *a³* is secured between the first named sections and thus affords a riser for communicating with an intake manifold *b*.

The generator driven from the internal combustion engine which is served by the carburetor *a*, is shown at *G*, the shunt field of which is indicated at *g*. Resistance *r* is connected in the shunt field circuit by means of wires *g'*, contact segments *r'* and *r''* being connected to the resistance segments through lead wires *r³*. A switch arm *R* is pivoted at *r⁴* to be turned to engage the contact segments *r'* selectively.

A shaft *c*, driven from the internal combustion engine which drives the generator *g*, rotates the governor *c'* which actuates governor rod *c²*. A throttle valve *d* is mounted in the riser section *a'* and is actuated by the governor rod *c²*. A manual throttle lever *e* actuates a second throttle valve *f* in the riser section *a''*, through a rod *e'* which connects the throttle valve with the manual lever *e*.

Pipe line *h* communicates with the riser section *a³* and with a cylinder *h'* within which piston *h²* is slidably mounted. A spring *h³* normally urges the piston to the right, as viewed in the figure, and this movement is transmitted to the lever *R* through link *h⁴*. When the depression in the riser section *a³* increases, piston *h²* is pulled to the left against the action of spring *h³* to cut out the resistance *r*, thus strengthening the generator field and throwing more load upon the engine. When the depression decreases, that is, when the engine is fully loaded, the spring *h³* moves the lever *R* to insert resistance in the generator field and thus reduces the output thereof and the load on the engine.

From the foregoing construction it will be apparent that, when the engine speed increases above a predetermined amount which indicates its ability to carry more load, the

governor c' operates to effect, either a partial or a total closing of the throttle valve d . This produces a depression in the riser section a^3 which results in movement of the piston h^2 to the left, overcoming the spring h^3 , and moving lever R to the left. In this manner, resistance is cut out of the field g and the generator output increases, thus increasing the load on the engine. When the engine is overloaded the reverse occurs and the generator output is decreased to enable the engine to speed up to a desired point.

The usual manual throttle operations are effected through lever e and throttle f , this throttle being located between the manifold and the riser section a^3 so that closing of the throttle f will not produce a vacuum or depression in the riser section a^3 and thus actuate the piston h^2 to cut out resistance and increase the generator output when the engine is throttled down. This prevents killing the engine when it is throttled down by means of the manually controlled throttle.

While the invention has been described with specific reference to the construction shown in the accompanying drawing, it is not to be limited, save as defined in the appended claim:

I claim as my invention:

30. A combination comprising an engine having a manifold, a generator driven by said engine, a field winding on said generator, an engine speed responsive device, a manually operated member and a generator field controlling mechanism, a riser section having a throttle valve therein, means to control the valve by the speed responsive device, a second section between the valve and manifold communicating with the field controlling mechanism, a third section having a throttle valve between the second section and the manifold, and means connecting the throttle valve in the third section to the manually operated member.

45. This specification signed this 7th day of May, A. D. 1929.
